Reuben H. Benjamin
By James Aldington, Amer. Sciclof, Atly's.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

GRIPPING DEVICE.

1,277,534.

Specification of Letters Patent. Patented Sept. 3, 1918.

Application filed July 26, 1915. Serial No. 42,106.

To all whom it may concern:

Be it known that I, REUBEN B. BENJAMIN, a citizen of the United States, residing at Chicago, in the county of Cook and State of Illinois, have invented new and useful Improvements in Gripping Devices, of which the following is a full, clear, concise, and exact description, reference being had to the accompanying drawing, forming a part of 10 this specification.

My invention relates to gripping devices and more specifically to lamp gripping sockets, that is, to lamp sockets provided with means for holding the lamp against accidental loosening due to vibration or like causes.

One of the objects of my invention is to improve upon devices of this character and to provide a simple and economical construction which will effectually hold the lamp in 20 the socket.

In the accompanying drawings in which I have illustrated one embodiment of my invention—

Figure 1 is a bottom plan view of a skeleton lamp socket embodying my invention; Fig. 2 is a section on the line 2—2 of Fig. 1; and

Fig. 3 is a section on the line 3—3 of Fig. 1.

Referring now to the drawings in detail, 30 I have shown my invention in connection with a skeleton lamp socket (that is, a socket in which insulation is not provided around the shell contact) comprising an insulating base 10 which supports the contacts and the binding terminals, and by means of which the device is secured in place on a support, a threaded shell contact 11, and a center contact 12, both supported on the base 10 for engagement with the corresponding contacts 35 of the lamp base, binding terminals 13 and 14 connected with the shell and center contacts, respectively, securing means 15 and 16 for fastening the contacts and binding terminals in place on the base 10, and a

40 spring lamp gripping device 18 for engaging the shell contact on the lamp base as the latter is inserted in the contact 11 to hold it in place therein. The base 10 is provided with a U-shaped boss 19 forming a backing 45 for the center contact 12 and also serving to keep the contacts 12 and 11 separate, openings 20 through which the securing means 15 extends, recesses 21 in which the heads of the fastening means 15 and 16 are seated, 50 recesses 22 in which the binding terminals

13 and 14 are located, and openings 23 through which the securing means 16 extends.

The boss 19 is provided with lateral extensions 24 having openings 25 therein into 60 which the spring lamp gripping device 18 extends.

The threaded shell contact 11 is provided with an inwardly extending flange 26 through which the securing means 15 and 16 65 extend to hold the contact in place on the base, and is cut away at 27 to permit the binding terminal 14 to be connected with the center contact 12. The shell 11 is also provided with helical slots 28 on opposite 70 sides which follow the pitch of the threads and through which portions of the lamp gripping device 18 extend for engagement with the lamp base. The center contact 12 comprises a spring tongue portion 29 for engagement with the center contact of the lamp 75 and a base portion 30 through which one of the securing means 15 extends to hold the contact on the base 10 and in electrical connection with the binding terminal 14. 80

The binding terminals 13 and 14 are duplicates and each comprises a binding plate 31 having an upturned wire retaining portion 32, a binding screw 33 threaded into the plate 31 and a binding plate 34 between 85 which and the binding plate 31 the end of the wire is gripped.

For the securing means 15 and 16 I have used hollow rivets or eyelets which are flanged over as shown at 35, 36 and 37 to 90 hold the contacts and binding terminals in electrical connection with each other and also to hold them on the base 10.

The lamp gripping device 18 comprises a U-shaped portion 38, the opposite sides of 95 which extend through the slots 28 into engagement with the lamp base, and two leg portions 39 extending substantially at right angles to the plane of the U-shaped portion 38, the ends of which are seated and fit 100 loosely in the openings 25 in the base 10.

The use and operation of my improved device is as follows: As the lamp base is screwed into the shell 11 the entering end of the base engages the parts of the U-shaped 105 portion 38 which extend within the shell and force the latter outwardly sufficiently to allow the base to make contact with the center contact 12 of the socket. The tension of the gripping device 18 is such as to hold 110

these engaged portions tightly against the shell contact of the lamp base so that the lamp will not be accidentally unscrewed or shaken loose.

5 It will be seen that I provide a lamp gripping device which is very simple in construction and efficient in use, and which is well adapted for use with a skeleton lamp socket.

10 Having thus described my invention what I claim as new and desire to secure by Letters Patent is:—

15 1. In a device of the class described an insulating base, a shell contact, gripping means for retaining a lamp base in place in said shell contact comprising a U-shaped portion for embracing said lamp base, and a leg portion extending at an angle to the plane of the U-shaped portion, said insulating base having an opening to receive said leg.

20 2. In a device of the class described an insulating base, a shell contact supported by and extending from said base, and yielding lamp clamping means positioned to be distorted as the lamp base is inserted in the shell contact supported directly by said insulating base, said yielding means comprising an elongated portion extending from said insulating base, alongside said shell, substantially parallel to the axis of said shell, and a portion supported by said elongated portion for exerting pressure on the lamp-base.

25 3. In a device of the class described an insulating base, a shell contact supported by and extending from said base, and yielding lamp clamping means positioned to be distorted as the lamp is inserted in the shell contact supported directly by said base, said yielding means comprising a portion extending from and supported directly by said base substantially parallel to the axis of said shell, and two portions connected together 40 and to said first portion for engaging opposite sides of the lamp base as it is inserted.

4. In a device of the class described an insulating base, a shell contact supported by and extending from said base, and yielding

50 lamp clamping means positioned to be distorted as the lamp is inserted in the shell contact supported by said base, said yielding means comprising a yoke having portions for engaging opposite sides of the lamp base and comprising also two portions supported directly by said base, one extending from each side of the yoke substantially parallel to the axis of the shell.

55 5. In a device of the class described an insulating base, a shell contact having its outer part exposed supported by and extending from said base, and yielding lamp clamping means positioned to be distorted as the lamp is inserted in the shell contact supported by said base, said yielding means comprising a yoke having portions for engaging opposite sides of the lamp base and two portions, one extending from each side of the yoke substantially parallel to the axis 60 of the shell, said base having openings into which said parallel portions extend.

65 6. A receptacle comprising an insulating base and a shell contact supported thereby, yielding lamp clamping means positioned to be distorted as the lamp base is inserted in the shell contact, said yielding means comprising a U-shaped portion for embracing said lamp base and two leg portions extending at an angle to the plane of the U-shaped portion, said insulating base having 70 openings into which the leg portions extend and fit loosely.

70 7. In a device of the class described an insulating base, a shell contact having its outer part exposed supported by and extending from said base, and yielding lamp clamping means positioned to be distorted as the lamp is inserted in the shell contact supported by said base, said yielding means comprising a yoke having portions for engaging opposite sides of the lamp base and two portions, one extending from each side of the yoke substantially parallel to the axis 75 of the shell, said shell having openings through which portions of the yoke extend.

90 In witness whereof, I have hereunto subscribed my name.

REUBEN B. BENJAMIN.
